UNITED STATES PATENT OFFICE.

ANNA OTTO SCHUCKMAN, OF LINCOLN, NEBRASKA.

CULINARY APPARATUS.

SPECIFICATION forming part of Letters Patent No. 400,255, dated March 26, 1889.

Application filed November 14, 1888. Serial No. 290,802. (No model.)

To all whom it may concern:

Be it known that I, ANNA OTTO SCHUCKMAN, of Lincoln, in Lancaster county, Nebraska, a citizen of the United States, residing at Lincoln, in the county of Lancaster and State of Nebraska, have invented certain new and useful Improvements in Culinary Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to an improvement in culinary devices, and especially to the class of domestic steamers designed to be attached to an ordinary cooking vessel or boiler to facilitate the operation of cooking or for the 20 purpose of steaming or warming food.

It consists in certain details of construction and arrangement of parts, hereinafter more specifically described in the accompanying specification, illustrated in the drawings, and 25 pointed out in the claims.

In the accompanying drawings, Figure 1 is a perspective of my device. Fig. 2 is a side elevation. Fig. 3 is a central cross-section. Fig. 4 is a vertical section of a cooking boiler 30 or vessel with my improvement attached, showing its position during the operation of cooking, and means of attachment and adjustment.

Referring more specifically to the drawings by letter, A is a metallic disk, which may be of any suitable size to fit within an ordinary cooking-vessel, and it is provided throughout its entire surface with fine perforations for the passage of steam. It is preferably made 40 slightly concavo-convex in shape, and has secured upon its upper or convex side an elbow-standard, B, consisting of an upright portion or arm, b, and a foot or horizontal arm, b'. Through the outer end of the foot b' are perforations c, to receive a screw-bolt, d, which passes down through the disk A at or near its center, and is provided with a nut, e, fitted upon its outer end, beneath the disk, for securing the disk to the standard.

45 Upon the upright portion b of the standard is provided a slotted clevis-shaped slide, D, through the slot a of which the upright b pro-

jects, enabling the clevis to slide freely up or down upon the upright; but its motion is controlled by a thumb-screw, E, projecting 55 through the outer arm of the clevis and bearing against the upright, as shown in Figs. 1 and 2.

In devices heretofore employed for steaming or warming articles of food, or for preventing them from burning or scorching by contact with the bottom of the cooking-vessel, it has usually been necessary to specially adapt the vessel to support the device by providing lugs or flanges within the vessel or 60 appliances to its cover for suspending it therefrom; or they have been made to consist of a cage, box, or disk having a rod or hook secured at one side for suspending it from the edge of the vessel, in which case the support, 65 being entirely upon one side, permits the opposite side to sag down, so that the bottom of the disk or basket, when loaded, assumes an inclined or slanting position, allowing the articles thereon to slide downward to the lowest 70 side.

The object of my invention is to overcome these objections by providing a simple and cheap device capable of being applied to any ordinary cooking vessel or steamer, and which 80 is suspended from its center, so that when loaded it will occupy a horizontal position within the vessel, the downward pressure being uniform on all sides.

The slide or clasp D is designed to embrace 85 and fit over the upper edge of a cooking-vessel to which my device is applied, and adjustably secure it within the same, by means of the thumb-screw, at any desired distance from the bottom, as shown in Fig. 4.

I am aware that cooking attachments have been heretofore used consisting of an open-work cage, box, or disk to contain the articles to be cooked, and adapted to be suspended or supported within a cooking vessel or boiler; 90 also, that means have been provided for adjusting the height of such device within the cooking-vessel, and I do not claim this, broadly.

Having thus described my invention, what I claim, and desire to secure by Letters Patent, 95 is—

1. In a steaming attachment for boilers, the combination of the perforated disk A, the elbow-shaped standard having its foot riveted

or bolted to the center of the disk and its upright at right angles with the rim, and the clevis-shaped clamp D, adapted to slide upon the upright and provided with a slot, a, and 5 set-screw E, for adjusting same upon the standard, substantially as described.

2. The concavo-convex perforated disk A, the elbow-shaped arm B, having its foot secured to the center of the convex face of the 10 disk, and the clevis-shaped clamp-hook D, provided with the slot a, to receive the arm

and adapt the hook to slide thereon, and the set-screw E, to adjust it to position, all combined and arranged substantially as and for the purpose described.

In testimony whereof I affix my signature in presence of two witnesses.

ANNA OTTO SCHUCKMAN.

Witnesses:

JOSEPH ADDISON MARSHALL,
ANNIE ROWENA SCHUCKMAN.
